UNITED STATES PATENT OFFICE.

WILLIAM ALEXANDER CRAMMOND, OF NEW YORK, N. Y.

STEAM-PIPE FOR GAS-HOLDERS.

1,018,033.

Specification of Letters Patent.

Patented Feb. 20, 1912.

Application filed September 14, 1911. Serial No. 649,315.

To all whom it may concern:

Be it known that I, WILLIAM ALEXANDER CRAMMOND, a citizen of the United States, and resident of the borough of Manhattan, 5 city, county, and State of New York, have invented certain new and useful Improvements in Steam-Pipes for Gas-Holders, of which the following is a specification.

My invention relates to means for supplying a heating agent, and particularly steam, to the water seal cups of telescopic gas holders, for the purpose of preventing the freezing of water during the winter. In order to accomplish this result I have provided a novel construction which is very durable, of comparatively light weight and great rigidity to resist the disturbing effects of wind, yet readily flexible in response to the normal up and down movements of the 20 gas holder, and having joints which remain tight under all conditions.

The subject matter of my present application was disclosed, substantially, in my earlier application Serial No. 567,135, as 25 filed originally in the United States Patent Office on June 16, 1910, which application has matured into Letters Patent No. 1,006,830, dated October 24, 1911.

I will now proceed to describe a specific 30 embodiment of my present invention, as illustrated in the accompanying drawings, and will then point out the novel features of the invention in the appended claims.

Figure 1 is a partial side elevation of a 35 gas holder provided with my improved heating pipe; Fig. 2 is a vertical section on line 2—2 of Fig. 1; Fig. 3 is a horizontal section on line 3—3 of Fig. 1; Fig. 4 is a longitudinal section of one of the pipe couplings 40 employed by me; and Fig. 5 shows the heating connection to the lowermost holder section.

I do not claim herein the specific construction 45 of the pipe coupling, as this forms the subject-matter of my earlier application referred to above.

In Figs. 1 and 2, I have shown three successive movable sections A, B, C of a telescopic gas holder, which in its general features is of the customary construction. 50 Each of these sections is provided at its upper end with an inverted cup formed by a depending inner flange, such as A', B', arranged to dip into the water seal in the cup, such as B'', C'', formed by an upwardly 55 extending outer flange at the lower end of the

next section above, this being a well-known construction. On the inverted cup at the upper end of each holder section is secured a bracket or carrier D, preferably provided with braces D', for a vertical metal pipe section E. The upper end of each pipe section E is connected with a coupling of the character shown in Fig. 4. This coupling comprises a member F threaded internally 60 to fit the upper end of the pipe E and having an interior passage F' which is substantially in line with the pipe E adjacent thereto, but has its other end at a right angle to said pipe. At said end the member F is 65 fitted into a socket formed at one end of the coupling member G. This end is screw-threaded to receive a gland H which surrounds the adjacent horizontal end of the coupling member F and makes a tight joint 70 with the aid of a suitable packing J. In line with the axis of the horizontal upper end of the member F, an external lug or axle pin F² is projected therefrom, and this lug is 75 engaged by a plate K made integral with the coupling member G, or secured thereto rigidly. The lug or pin F² and the horizontal upper end of the coupling member F form a bearing or trunnion on which the 80 other coupling member can swing, while lateral movement of this member G (lengthwise of the pivot) is limited or prevented by the end of the member F and by the shoulder 85 adjacent to the lug F². The coupling member G has an internal passage G' having a 90 substantially horizontal lower end to register with the horizontal upper end of the passage F', and a vertical upper end provided with a screw thread to receive the lower end of a swinging metal pipe section 95 L. The upper end of the pipe section L is connected, by means of a coupling of the same construction as described above, with another swinging metal pipe section M. It will be understood from Figs. 2 and 4 that 100 the pipe sections E, L and M always remain in the same plane, notwithstanding the swinging movement of the sections L, M. The upper end of the pipe section M is screwed into a coupling member F of the 105 same construction as described above, said member having a gland H and a trunnion pin or lug F². The mating coupling member g is T-shaped and horizontal, the central portion of the T communicating with the 110 passage of the coupling member F. This member g and the bearing plate k for the

trunnion lug F^2 , are carried rigidly by the upper end of the corresponding gas holder section. The second passage-way of the T-shaped coupling member g communicates 5 with a pipe N provided with a regulating valve N' and leading to nozzles N^2 adapted to discharge the heating agent (steam) into the cup of the respective holder section, so as to prevent the freezing of the water contained therein. A pet cock N^3 may be provided immediately above the nozzles. The third passage-way of the T-shaped coupling 10 g leads to a horizontal connecting pipe O communicating with the lower end of the 15 next vertical pipe section E . P indicates the customary frame work having tracks P' for rollers R carried by the telescoping sections of the gas holder. The nozzles N^2 of the lowermost holder section receive a 20 supply of heating agent (steam) in any suitable manner. For instance, the swinging pipe m depending from said lowermost section may be connected, through the medium of another swinging pipe l , with a stationary 25 steam supply pipe e suitably supported on the platform S (Fig. 5). That is to say, the construction is the same as described above, except that the lowermost vertical pipe e is fixed instead of being carried by 30 one of the movable holder sections.

With my improved arrangement of pipes, a very efficient and durable construction is obtained. The length of the pipe sections e , E is preferably about one-third of the height 35 of the gas holder sections, or slightly more. The vertical and the swinging pipe sections being made of metal, they are of sufficient rigidity to resist bending strains due to wind, and are not liable to be blown against, 40 and become entangled with, parts of the frame work. The joints remain tight under all conditions, and the weight of the pipes is borne just as much by the upper ends of the pipe sections e , E as by the coupling members g . The strains at the joints are thus 45 reduced, thus increasing the life of the device. The arrangement of the jointed pipe sections (such as E , L , M) in the same plane, transverse to the several parallel axes or 50 pivots of such jointed sections, is a very important and advantageous feature of the construction. It causes the connected swinging sections (L , M) to turn in the same plane, and avoids or diminishes the tendency 55 of the pipe sections to twist or swing from their proper position, either when the holder sections move up and down, or when a lateral strain is exerted by winds. I thus avoid all strain on the threads engaged by the 60 glands H , which threads are liable to receive irregular strains when the pipe sections are not in the same plane of movement, especially in case the joint is stiff.

It will be observed that all the pipe sections E are substantially in the same ver-

tical plane, so that in case of installing the device or making repairs thereto, all of said pipe sections can be reached from one ladder, without changing its position.

Various modifications may be made without departing from the nature of my invention as set forth in the appended claims. 70

I claim:

1. In a telescopic sectional gas holder having cups to form liquid seals at the junction of two sections, a heating arrangement comprising an upper pipe section located at the top of a holder section and arranged to discharge a heating agent into the cup, a vertical lower pipe section adapted to receive a supply of heating agent, said upper section being movable up and down relatively to said lower section, and swinging rigid pipe sections connected with each other and with said upper and lower sections by parallel horizontal pivot joints. 80

2. In a telescopic sectional gas holder having cups to form liquid seals at the junction of two sections, a heating arrangement comprising an upper pipe section located at the top of a holder section and arranged to discharge a heating agent into the cup, a vertical lower pipe section adapted to receive a supply of heating agent, said upper section being movable up and down relatively to said lower section, and swinging rigid pipe sections connected with each other and with said upper and lower sections by parallel horizontal pivot joints, the vertical pipe section and the swinging sections being located 90 in the same plane, transverse to said parallel pivots. 95

3. In a telescopic sectional gas holder having cups to form liquid seals at the junction of two sections, a heating arrangement comprising an upper pipe section located at the top of a holder section and arranged to discharge a heating agent into the cup, a lower pipe section adapted to receive a supply of heating agent, said upper section being movable up and down relatively to said lower section, and swinging rigid pipe sections connected with each other and with said upper and lower sections by parallel horizontal pivot joints. 100

4. In a telescopic sectional gas holder having cups to form liquid seals at the junction of two sections, a heating arrangement comprising an upper pipe section located at the top of a holder section and arranged to discharge a heating agent into the cup, a lower pipe section adapted to receive a supply of heating agent, said upper section being movable up and down relatively to said lower section, and swinging rigid pipe sections connected with each other and with said upper and lower sections by parallel horizontal pivot joints, said swinging sections being arranged to swing in the same plane. 110

5. In a telescopic sectional gas holder hav-

- ing cups to form liquid seals at the junction of two sections, a heating arrangement comprising an upper pipe section located at the top of a holder section and arranged to discharge a heating agent into the cup, a lower pipe section adapted to receive a supply of heating agent, said upper section being movable up and down relatively to said lower section, swinging rigid pipe sections piv-
totally connected with each other and with said upper and lower sections, and a connecting pipe section extending from the upper pipe section of a holder section to the lower pipe section of the same holder section.
6. In a telescopic sectional gas holder having cups to form liquid seals at the junction of two sections, a heating arrangement comprising an upper pipe section located at the top of a holder section and arranged to discharge a heating agent into the cup, a vertical lower section adapted to receive a supply of heating agent, said upper section being movable up and down relatively to said lower section, swinging rigid pipe sections connected with each other and with said upper and lower sections by horizontal pivot joints, and a connecting pipe section extending from the upper pipe section of a holder section to the lower pipe section of the same holder section, the vertical lower pipe sections lying substantially in the same vertical plane.
7. In a telescopic sectional gas holder having cups to form liquid seals at the junction of two sections, a heating arrangement comprising an upper pipe section located at the top of a holder section and arranged to discharge a heating agent into the cup, a vertical lower section adapted to receive a supply of heating agent, said upper section being movable up and down relatively to said lower section, swinging rigid pipe sections connected with each other and with said upper and lower sections by horizontal pivot joints, and a connecting pipe section extending from the upper pipe section of a holder section to the lower pipe section of the same holder section, the vertical lower pipe sections lying substantially in the same vertical plane.
15. 6. In a telescopic sectional gas holder having cups to form liquid seals at the junction of two sections, a heating arrangement comprising an upper pipe section located at the top of a holder section and arranged to discharge a heating agent into the cup, a lower pipe section adapted to receive a supply of heating agent, said upper section being movable up and down relatively to said lower section, swinging rigid pipe sections piv-
totally connected with each other and with said upper and lower sections, and a connecting pipe section extending from the upper pipe section of a holder section to the lower pipe section of the same holder sec-
tion, the lower pipe sections of the several holder sections lying substantially in the same vertical plane.
16. 7. In a telescopic sectional gas holder having cups to form liquid seals at the junction of two sections, a heating arrangement comprising an upper pipe section located at the top of a holder section and arranged to discharge a heating agent into the cup, a vertical lower section adapted to receive a supply of heating agent, said upper section being movable up and down relatively to said lower section, swinging rigid pipe sections connected with each other and with said upper and lower sections by horizontal pivot joints, and a connecting pipe section extending from the upper pipe section of a holder section to the lower pipe section of the same holder section, the vertical lower pipe sections lying substantially in the same vertical plane.
17. In testimony whereof I have signed this specification in the presence of two sub-
scribing witnesses.
